UNITED STATES PATENT OFFICE.

THADDEUS BAKER MOORER, OF CHARLESTON, SOUTH CAROLINA.

RHEOSTAT.

Application filed September 16, 1924. Serial No. 738,033.

This invention relates to improvements in rheostats, and consists of the constructions, combinations and arrangements herein described and claimed.

5 An object of the invention is to provide a rheostat which permits the effective use of alternating current for welding purposes.

Another object of the invention is to provide a rheostat of the grid type having a supplementary or auxiliary grid by the particular use of which alternating current may be 10 adapted to welding purposes.

Other objects and advantages appear in the following specification, reference being had 15 to the accompanying drawing, in which

Figure 1 is a front elevation of the improved rheostat.

Figure 2 is a side elevation.

Figure 3 is a diagram illustrating the circuit involved.

Figure 4 is a detail plan view of one of the grid banks.

Figure 5 is a detail sectional view of a portion of the rheostat illustrating the particular 20 manner of mounting the grids.

In carrying out the invention use is made 30 of an open frame composed of uprights or legs 1, suitable cross pieces 2 and a plurality of end cross bars 3. These are located at each end of the frame (Fig. 2), and there are three pairs of the cross bars 3 to support as many banks of grids. The cross bars, legs, etc. are suitably fastened together as by means 35 of rivets. A suitable insulating panel 4 is fastened to the front of the frame, covering approximately one-half of the distance.

As mentioned before, there are three banks 40 of grids. These are designated 5, 6 and 7. The bank 7 is called a supplementary or auxiliary grid bank because by means of it and its control, alternating current has been found 45 usable for welding purposes. A distinct improvement in the mounting of the grid banks has been worked out, and inasmuch as each bank is mounted alike, the description of the mounting of the upper bank 7 will suffice for the three.

Rods 8 and 9 extend from one cross bar 3 to the other. The ends of the rods are threaded 50 to receive a pair of nuts 10 and 11 (Fig. 5). A mica or other insulating sleeve 12 is slipped upon each rod, 9 for example. The ends of the sleeve 12 abut similar metal washers 13. A metal collar 14, preferably of iron or brass, 55 is then fitted upon each end of the mica sleeve 12.

A mica washer 15 comes next to the collar 14, and then follows a plurality of copper washers 16 and metallic grids 17 in alternation. Figure 5 shows two of the grids 17 separated from the next similar set by a mica washer 18 on one rod and connected by a lug 40 on the other rod to the next set of grids which is made in the same manner as the first and in turn is connected by a lug 40 to the set 60 following. Thus the lugs 40 and mica washers 18 alternate, connecting the parallel sets of grids in series.

In the banks 5 and 6 a slightly different arrangement prevails. In both instances the 70 grids are connected three in parallel. These parallel sets are then connected in series. It is to be noted that the only difference is that three grids are connected together in the case of the banks 5 and 6, whereas in the bank 75 7 two of the grids are connected together.

Upon reference to Figure 1 it is seen that the panel 4 is furnished with two terminal posts 19 and 20 at which the wires 21 and 22 from a 110 volt A. C. transformer are connected. The terminal posts are in connection with the contacts 23 and 24 of the knife switch 25, the pivotal mountings of which are connected by means of a wire 26 with the central grid bank 6, and a wire 27 with the 80 handle of a welding tool (see Fig. 3).

A wire 28 leads from the usual ground connection to the pivot 29 of a single, primary knife switch 30. The switch 30 has a plurality of contacts 31 which are respectively 90 joined by means of suitable electrical conductors 32 with certain ones of the grids in the upper bank 7. The switch 30 controls approximately one-half of the upper bank.

Similarly, a single blade, secondary knife 95 switch 33 controls the other half of the upper grid bank. The pivotal point 34 of this switch is connected in shunt by means of a wire 35 with the wire 28 at the pivot 29. The switch 33 has a plurality of contacts 36 100 which are connected with certain ones of the upper grids by means of conductors 37.

A wire 39 connects the upper bank 7 with the lower bank 5. A wire 38 connects the last contact 36 with a predetermined set of grids 105 in the lower bank 5. Obviously the connection 39 may be made adjustable, for example by means of a clip, so that more or less of the grids in the lower bank may be brought into play.

Reference is again made to Figure 5. Certain connected sets of grids have copper lugs

40 beside them. These lugs are placed upon the mica sleeve 12 between sets of grids. The lugs extend out far enough to permit reaching them for the making of a connection such 5 as was just described in connection with the wire 39. These may be needed for the adjustment of the connectors 32 and 37 as much so as of the wire 39, and the outstanding lugs 40 permit of such adjustment. The connectors 10 may be clipped on where desired.

Upon closure of the switch 25 current flows from the transformer mentioned over the wire 27 to the welding electrode holder, passing through the ground connection to the 15 wire 28. Presume that the primary switch 30 has been moved down far enough to engage the first contact 31. All of the grids in the upper bank 7 must be traversed by the current before it reaches the wire 39 and 20 enters the lower bank 5. Thence it passes to the bank 6, with which it is connected at 41, emerging at the wire 26 and returning to the source of supply.

It is obvious that further closing of the 25 primary switch 30 will cut out more of the grids in the bank 7 so that the resistance is lowered and the welding heat is increased. Should even greater heat be needed than the manipulation of the primary switch 30 will 30 afford, recourse is had to the secondary switch 33. Upon successive engagement of the contacts 36 more and more of the grids in the upper bank will be cut out until the last contact 36 is engaged, whereupon even one 35 section of the lower grid 5 is cut out.

The main purpose of the invention is to provide a rheostat of the grid type by means of which alternating current may be used in conjunction with bare welding electrodes for 40 making a weld. Other and known types of A. C. rheostats are able to use only the various makes of coated electrodes. This coat forms a slag which maintains the arc. This slag causes the deposited metal to be full of 45 small holes so that it assumes a spongy appearance which makes it totally unsuited for use in places where steam and water tight connections must be made.

The improved rheostat eliminates the 50 present disadvantages, chiefly by virtue of the fact that it permits the use of bare electrodes with alternating current. Obviously, it is also possible to use coated electrodes when desired, but it is to avoid such use that 55 the particular rheostat has been designed. The auxiliary bank of grids 7 and the switches 30 and 33 which control them provide the necessary fine adjustment of heat required to burn a bare electrode successfully. 60 This type of rheostat may be used on practically any voltage up to 550 by simply introducing the correct number of sets of grids in the circuit.

I claim:

1. A rheostat comprising a succession of 65 insulated grid sections in series connection with a series of successive sections forming part thereof provided with separate cut-out connection to successively arranged switch contact members, and a single blade switch 70 member mounted for movement progressively to engage and connect in series said successive contact members whereby movement of the switch blade to engage said contacts is effective progressively to decrease the grid resistance 75 interposed in the circuit.

2. A rheostat comprising a succession of 80 insulated grid sections in series connection with a series of successive sections forming part thereof provided with separate cut-out connections to successively arranged switch contact members, a single switch member connected in shunt around said series aforesaid; and mounted for movement progressively 85 to engage said contact members, first, to interpose said entire series in the resistance circuit, and thereafter progressively to cut-out successive sections from said circuit.

3. A rheostat comprising a plurality of 90 banks of grids in series connection, one of said banks comprising a succession of insulated grid sections in series connection, each section being provided with individual cut-out connection to successively arranged switch contact members, and a single switch member 95 mounted for movement progressively to engage and connect in series said successive individual cut-out contact members whereby movement of said switch member to engage said contacts progressively decreases the grid resistance interposed in the 100 circuit.

4. A rheostat comprising a plurality of 105 banks of grids in series connection, one of said banks comprising a succession of insulated grid sections in series connection, each section being provided with individual cut-out connection to successively arranged switch contact members, and a single switch member 110 mounted for movement progressively to engage and connect in series said successive individual cut-out contact members whereby movement of said switch member to engage said contacts progressively decreases the grid resistance interposed in the 115 circuit, one of said other banks of grids having a series of successively arranged insulated grid sections, each with a connector element projecting therefrom, and a connection from the end or final switch contact of the first mentioned bank selectively engageable with intermediate projecting connector elements of the second mentioned bank further and selectively to decrease interposed grid resistance upon the final closing of the aforesaid switch member.

THADDEUS BAKER MOORER.
